CLAIM

The ornamental design for a food preparation board as shown and described.

DESCRIPTION

FIG. 1 is a perspective view of a food preparation board in a closed configuration, showing our new design;

FIG. 2 is a top view thereof;

FIG. 3 is a bottom view thereof;

FIG. 4 is a left side view thereof;

FIG. 5 is a right side view thereof;

FIG. 6 is a front elevation view thereof;

FIG. 7 is a rear elevation view thereof;

FIG. 8 is a perspective view of a food preparation board in an open configuration, showing our new design;

FIG. 9 is a top view thereof;

FIG. 10 is a bottom view thereof;

FIG. 11 is a left side view thereof;

FIG. 12 is a right side view thereof;

FIG. 13 is a front elevation view thereof;

FIG. 14 is a rear elevation view thereof;

FIG. 15 is a perspective view of a food preparation board in an alternate open configuration, showing our new design, shown further in use with exemplary storage containers;

FIG. 16 is a top view thereof;

FIG. 17 is a bottom view thereof;

FIG. 18 is a left side view thereof;

FIG. 19 is a right side view thereof;

FIG. 20 is a front elevation view thereof; and,

FIG. 21 is a rear elevation view thereof.

The broken lines in the drawings represent parts of the article as well as environmental subject matter of exemplary storage containers. None of the broken lines form part of the claimed design.
